HYDROFOIL WATER SKI

John M. Diehl, 5729 Elder Place, and Rudolph J. Kame-
nick, 5815 Raymond Road, both of Madison, Wis.

Filed Sept. 28, 1964, Ser. No. 81,886

Term of patent 14 years

(Cl. D71—1)

FIG. 1

FIG. 2

FIG. 3

FIG. 4

FIG. 7

FIG. 5

FIG. 6

FIGURE 1 is a side elevation of the hydrofoil water ski showing our new design;

FIGURE 2 is a rear elevational view thereof;

FIGURE 3 is a top plan view thereof;

FIGURE 4 is a side elevational view of a modified form of the hydrofoil water ski shown in FIGURE 1;

FIGURE 5 is a rear elevation of the embodiment of FIGURE 4;

FIGURE 6 is a plan view from the bottom of the embodiment of FIGURE 4;

FIGURE 7 is a top plan view of the form shown in FIGURE 1, the modification shown in FIGURE 4 having the same appearance in top plan except for the width of the hydrofoil.

We claim:

The ornamental design for a hydrofoil water ski, as shown and described.
